UNITED STATES PATENT OFFICE.

CHARLES E. SCHMUNK, OF PITTSBURG, PENNSYLVANIA.

APPARATUS FOR MANUFACTURING ARTICLES OF GLASSWARE.

SPECIFICATION forming part of Letters Patent No. 604,908, dated May 31, 1898.

Application filed October 16, 1897. Serial No. 655,385. (No model.)

To all whom it may concern:

Be it known that I, CHARLES E. SCHMUNK, a resident of Pittsburg, in the county of Allegheny and State of Pennsylvania, have invented a new and useful Improvement in Apparatus for the Manufacture of Articles of Glassware; and I do hereby declare the following to be a full, clear, and exact description thereof.

10 My invention relates to machines for manufacturing articles of glassware, such as lamp-chimneys, bottles, &c.

The object of my invention is to provide a form of apparatus by the use of which lamp-chimneys, bottles, and like articles can be made with great speed and accuracy without the aid of skilled labor, whereby the articles may be produced in great quantities and at less cost.

20 My invention comprises, generally stated, a suitable frame with a mold-support mounted therein adapted to revolve in a vertical plane, the mechanism for rotating the mold, as well as that for revolving the mold-support, being 25 operated by the act of closing and opening the mold, all of which will be more fully herein-after set forth and claimed.

To enable others skilled in the art to make and use my invention, I will describe the same 30 more fully, referring to the accompanying drawings, in which—

Figure 1 is a front view, partly in section, of my improved machine, showing the article in the act of being blown. Fig. 2 is a side view of same. Fig. 3 is a plan view, partly in section. Fig. 4 is a perspective view of the mold-support. Fig. 5 is a detail.

Like letters indicate like parts in each of the figures.

40 In the accompanying drawings I have illustrated my invention as applied to the blowing of lamp-chimneys; but I do not wish to be understood as limiting myself in any manner to the use of my machine for making any particular article, but wish to include within its scope all other articles which it may be found expedient to make by the use of said machine.

The letter A designates a suitable frame upon which the apparatus is mounted.

50 Mounted in the frame A and adapted to revolve therein is the mold-support B, said mold-support in the case illustrated being

rectangular in form and having the platforms b b' b² b³. Any other suitable construction of the mold-support, however, may be employed. 55 The mold-support B has the diagonal braces B', which serve to strengthen the support. Projecting from the side of the central boss or hub B² is the shaft c, said shaft being journaled within the journal-box c', bolted to the 60 frame A and supported thereby. At the outer end of the shaft c is mounted the pinion c². Each of the platforms b b' b² b³ has a circular plate d, fitting within a recess in said platform, the upper face of said circular plate having a dovetail d' formed thereon, adapted to engage with a dovetail recess e' in the bottom e of the partible mold E. This partible mold E, which in this instance is a lamp-chimney mold, is formed of the two halves hinged together by means of the pin e², which passes through the lugs e³, formed on each half of said mold. A spring f encircles the pin e², the ends of said spring being secured to the halves at f', the action of said spring being to 75 hold said halves normally open. Threaded into the circular plates d are the studs g, which carry the bevel-pinions g'. These bevel-pinions g' mesh with like bevel-pinions h, mounted on the short shafts h', which are 80 mounted in bearing-blocks h² on the inside of the mold-support B. Clutches h³, having the conical clutch-recesses h⁴, are mounted rigidly on the shafts h'. Mounted in bearings i in the frame A is the clutch i, said 85 clutch i being always in position to engage with one of the clutches h³ when one of the molds is in position for operation. The clutch-shaft i² has the annular groove i³ formed therein. Studs k' on the bifurcated 90 arm k engage the annular groove i³ at opposite points, said bifurcated arm k being secured to the vertical shaft l. This vertical shaft l is journaled within suitable bearings l' in the bracket A², secured to the frame A. Secured to the upper end of the shaft l is the 95 curved arm m, said arm having the curved slot m' formed therein. A stud n' on a lever n engages with the curved slot m' in the arm m. This lever n is rigidly secured to the stud o, journaled in the frame, said stud having the bevel-pinion o' mounted thereon. The outer end of the lever n has the idle-roller n² mounted therein, said idle-roller be-

ing adapted to move in contact with the base *e* of the portable mold *E*, so as to close the same in the manner more fully hereinafter set forth. The clutch-shaft *i*² is keyed to the 5. shaft *p* by the ordinary groove-and-feather connection, whereby the clutch-shaft *i*² is free to slide back and forth on said shaft *p*, but rotates with the said shaft *p*. This shaft *p* is journaled within suitable bearings *A*³ on 10 the bracket *A*², and the outer end of said shaft has the cone-shaped frictional head *r*. A vertical power-shaft *s*, driven by any suitable power, has its upper end journaled in bearings in the bracket *A*², and secured to said 15 shaft *s* are the cam-disks *s'* and *s*², said disks having the cam-faces *s*³ *s*⁴, respectively. The disks *s'* *s*² are so arranged on the shaft *s* with reference to each other that the cam-faces *s*³ *s*⁴ are brought alternately into contact with 20 the conical frictional head *r* of the shaft *p*. In this manner by the rotation of the shaft *s* the cam-disks *s'* *s*², by means of their cam-faces *s*³ *s*⁴, impart a partial rotary movement to the shaft *p* in one direction and then in 25 the opposite direction, as will more fully hereinafter appear. The bevel-pinion *o* meshes with a bevel-pinion *t*¹ on the shaft *t*, journaled in suitable bearings in the frame, the opposite end of said shaft *t* having a 30 bevel-pinion *t*², meshing with a bevel-pinion *t*³ on the shaft *t*⁴, said shaft *t*⁴ having at its opposite end a bevel-pinion *t*⁵, meshing with a bevel-pinion *t*⁶ on the shaft *t*⁷. The shaft *t*⁷ has at its opposite end bevel-pinion *t*⁸, meshing 35 with the bevel-pinion *t*⁹ on the stud *t*¹⁰, journaled in suitable bearings in the frame. To this stud *t*¹⁰ is secured the lever *u*, said lever having the friction-roller *u'* at the inner end thereof corresponding to the idle-roller *u*. 40 *n*² of the lever *n* and engaging with the bottom plate *e* of the mold at the opposite side from that of the lever *n*. By the above-described gearing mechanism any movement imparted to one of the levers *n* or *u* will 45 impart like movement to the opposite one. The pinion *t*⁹ meshes with a pinion *v*, mounted in suitable bearings in the frame, said pinion having the arm *v'* secured thereto. The outer end of the arm *v'* is connected by the 50 link or strap *v*² with the arm *v*³, secured to the shaft *w'*, upon which is mounted the gear-wheel *w*. This gear-wheel *w* meshes with the gear-wheel *c*², before referred to. At proper intervals on the outer face of the gear-wheel *w* are the seats *w*², said seats having 55 their bottoms inclined and adapted to receive the spring-latch *x* on the arm *v*³. This latch *x* fits within a suitable socket *x'* on the arm *v*³, and a spring is interposed between 60 said latch *x* and the socket *x'*, whereby said latch is forced normally into contact with the face of the gear-wheel *w* or into the seat *w*², according to the position of the arm *v*³, as will more fully hereinafter appear. Extending 65 up from the frame *A* is the upright rod *y*, said rod having the arms *y'* at suitable intervals, said arms having the bosses *y*²

formed with semicircular seats adapted to receive a portion of the pipe *H* and serve as a support and guide for the same during the blowing operation. One of the arms *y'* has a slot *y*³ formed therein, through which the clamping-jaws *y*⁴ pass, said jaws being normally closed by the spring *y*⁵, interposed between the outer ends of said jaws. These 70 jaws *y*⁴ are pivoted at *y*⁶, and they tend to grasp and hold the pipe and steady it during the blowing operation. The upper end of the pipe enters the seat *z*, formed at the outer end of the uppermost arm *y'*. This arm has the passage *z'* passing through and connecting with the air-passage of the pipe. A suitable packing-ring *z*² surrounds the outlet of the passage *z'*. A pipe *z*³ communicates with the passage *z'*, said pipe being connected with 85 suitable device for supplying air for the blowing operation. Within the frame *A*, in the lower portion thereof, is the tank or vessel *C*, adapted to contain suitable cooling fluid.

I do not wish to limit myself to the exact construction shown, as that may be modified without departing from the spirit of my invention.

The operation of my apparatus in the blowing of a lamp-chimney is as follows: With the parts in the position shown in Fig. 3 the mold-support *B* will have one of its mold-supporting platforms in proper position with reference to the frame for the blowing operation, and with the levers *n* and *u* in the positions shown in said figure the mold will be open and held open by means of the spring *f*. The gatherer gathers sufficient of the molten glass on the end of the pipe *H* and adjusts said pipe in the guides in the arm *y'*, so that the upper end of the pipe will enter the seat *z* in the uppermost arm, bringing the air-passage in said pipe into coincidence with the air-passage *z'*, passing through said arm. The pipe is then clamped in position by means of the clamping-jaws *y*⁴ and is then held securely in a vertical position. The length of the pipe is such that the molten glass at the end thereof hangs down within the space enclosed by the mold, so that when the mold is closed the glass will be completely inclosed thereby. The mold is closed by throwing the lever *n* over in the slot *m'* of the arm *m*. This movement of the lever *n* through the gearing mechanism described will also move the lever *u* around in line therewith. The inner ends of the levers *n* and *u*, with the idle rollers *n*² and *u'* in contact with the bottom of the mold, act to close the mold-halves around the molten glass. By throwing the lever *n* around into the position described the stud *n'* on said lever will act to advance the arm *m* and with it the arm *k*. As the arm *k* has the studs *k'* engaging with the annular groove *v*³ in the clutch-shaft *i*², the movement on the part of said arm *k* will advance the clutch *i* into engagement with the clutch *h*². At the same time this is done air is admitted through the pipe *H* from the supply-pipe *z*³ to blow

the glass within the mold. When the clutch i engages with the clutch h^3 , a rotary movement is imparted to the shaft h' , and a like movement is imparted through the bevel-gears h and g' to the vertical stud g , secured to the bottom plate d , which carries the mold. This rotary movement imparted to the bottom plate d , which supports the mold, is not, however, continuous in one direction, but the movement is reversed after said bottom plate has accomplished a half of a revolution. This reversing of the direction of rotation of the bottom plate d is caused by the action of the cam-disks s^1 and s^2 . With the cam-disk s^2 rotating in the direction of the arrow the cam-face s^4 , moving in contact with the frictional cone r , will act to rotate the shaft p in the direction indicated by the arrow a' . This will impart the rotary movement in one direction to the bottom plate d . When, however, the cam-face s^3 of the cam-disk s^1 comes in contact with the frictional cone r , the shaft p will be rotated in the direction of the arrow a^2 . This will act to reverse the movement of the bottom plate d . This rotation is imparted to the mold in order to prevent the formation of a fin on the lamp-chimney at the point where the two halves of the mold meet. If the rotary action of the mold were continuous in one direction, the neck of the chimney would be twisted and distorted, so that the chimneys produced would be imperfect; but by imparting a rotary movement in one direction and then in the other not only is the fin erased, but this twisting of the neck of the article is prevented, so that a perfect chimney without flaws is produced.

These chimneys are blown in what are commonly called "paste-molds," said molds having their inner faces coated with paste or other composition which will permit of the revolving of the mold without the sticking of the glass thereto. As soon as the chimney has been blown the operator by throwing back the lever n part way within the slot m' throws the clutch i out of engagement with the clutch h^3 and stops the rotation of the mold. At the same time the spring f' forces the mold-halves apart, and the chimney is removed. By moving the lever n farther within the slot m' until it reaches the outer end thereof the lever u is brought into the position shown in Fig. 3. It is of course to be understood that by moving the lever n' the lever n may be operated in the same manner. The movement of the lever n' to the position shown in Fig. 3 imparts a rotary movement to the bevel-gear t^3 , which meshes with the bevel-gear v . This rotation of the bevel-gear v raises the arm v' , secured thereto, and with it the arm v^3 , through the connecting-link v^2 . The partial movement of the lever u to throw the clutch i out of engagement with the clutch h^3 will raise the arm v^3 sufficiently to bring the latch x into engagement with the seat w^2 on the gear-wheel w . The further movement of the lever u to the position shown in Fig. 3 will cause further

rotation on the part of the bevel-gear v and a further elevation of the arm v' . The elevation of the arm v^3 when the latch x is in engagement with the seat w^2 will act to rotate the gear-wheel w . As said gear-wheel w meshes with the gear-wheel c^2 , a like movement is imparted to said last-mentioned gear-wheel. This gear-wheel c^2 being on the shaft c , a rotary movement is imparted to the mold-frame B , and the mold just used is lowered out of the way, while a fresh mold is brought into position for blowing, when the operations above described are repeated. The molds as they pass around in a circle formed by the rotation of the mold-support B pass into the tank or vessel C , where they are allowed to cool. This cooling of the molds is essential where paste-molds are employed in order to prevent the coating from burning out too rapidly.

By my invention I provide a form of apparatus for blowing lamp-chimneys, bottles, and like articles in quick succession without the employment of skilled labor, while at the same time I am able to produce perfect articles in large quantities and at less cost than where blown by hand.

What I claim as my invention, and desire to secure by Letters Patent, is—

1. In apparatus for forming articles of glass-ware, the combination with a suitable frame, of a rotary mold-support, a shaft therefor, a partible mold supported on said mold-support, a lever adapted to open and close said mold, bevel-pinions operated by said lever, an arm on one of said pinions, a shaft, a second movable arm, a gear-wheel on said shaft, the said gear-wheel having a stop, a link connecting said arms, said second arm being adapted to engage the stop on said gear-wheel, and a gear-wheel on the mold-supporting shaft with which said first-mentioned gear-wheel meshes, substantially as set forth.

2. In apparatus for forming articles of glass-ware, the combination with a suitable frame, of a rotary mold-support, a shaft therefor, a partible mold supported on said mold-support, a lever adapted to open and close said mold, bevel-pinions operated by said lever, an arm on one of said pinions, a shaft, a gear-wheel on said shaft, a second movable arm, a link connecting said arms, a latch on said second arm adapted to engage a seat formed in said gear-wheel, and a gear-wheel on the mold-supporting shaft with which said first-mentioned gear-wheel meshes, substantially as set forth.

3. In apparatus for forming articles of glass-ware, the combination with a suitable frame, of a rotary mold-support mounted therein, a gear-wheel on the mold-supporting shaft, a gear-wheel meshing therewith, a lever adapted to open and close the mold, and connections between said lever and the before-mentioned second gear-wheel, whereby an intermittent rotary movement is imparted to said gear-wheel, substantially as set forth.

4. In apparatus for forming articles of glass-

- ware, the combination with a suitable frame, of a rotary partible mold, mechanism for oscillating said mold, mechanism for closing said mold and connections between said mold-closing mechanism and the mechanism for oscillating said mold, whereby said oscillating mechanism is operated immediately after the closing of the mold, substantially as set forth.
5. In apparatus for forming articles of glass-
ware, the combination with a suitable frame, of a rotary mold-supporting plate, a partible mold mounted thereon, a lever adapted to close said mold, a clutch device, and connections between said lever and clutch for imparting an oscillating movement to said mold-supporting plate, substantially as set forth.
6. In apparatus for forming articles of glass-
ware, the combination with a suitable frame, of a rotary mold-supporting plate, a partible mold mounted thereon, a lever adapted to close said mold, a shaft having a clutch-face, connections between said plate and shaft, a reversing-shaft, a clutch thereon, and connections between said lever and clutch and clutch-face, substantially as set forth.
7. In apparatus for forming articles of glass-
ware, the combination with a suitable frame, of a rotary mold-supporting plate, a partible mold mounted thereon, a reversely-rotatable shaft having a clutch-face, connections between the plate and shaft, a sliding clutch adapted to engage said clutch-face, a lever adapted to close said partible mold, connections between said lever and said sliding clutch, and mechanism for rotating the clutch-shaft in opposite directions, substantially as set forth.
8. In apparatus for forming articles of glass-
ware, the combination with a suitable frame, of a rotary mold-supporting plate and a reversely-rotatable shaft having a clutch-face, a sliding clutch adapted to engage with said clutch-face, a lever adapted to close said mold, a stud on said lever, a movable arm having a curved slot therein with which the stud on said lever engages, connections between said arm and said sliding clutch, and mechanism for rotating the clutch-shaft in opposite directions, substantially as set forth.
9. In apparatus for forming articles of glass-
ware, the combination with a suitable frame, of a rotary mold supporting plate; a shaft, connections between said mold-supporting plate and said shaft, a power-driven shaft having cam-disks thereon, said cam-disks engaging said first-mentioned shaft at opposite sides thereof, substantially as set forth.
10. In apparatus for forming articles of glassware, the combination with a suitable frame, of a rotary mold-supporting plate, a shaft, connections between said mold-supporting plate and said shaft, said shaft having a conical friction-head, a power-shaft cam-disks on said power-shaft adapted to engage said conical head at opposite sides thereof, substantially as set forth.
11. In apparatus for forming articles of glassware, the combination with a suitable frame, of a rotary mold-support mounted therein adapted to revolve in a vertical plane, and having a plurality of mold-supporting faces, rotary mold-supporting plates mounted on said faces, mechanism for rotating said plates, an upright frame adapted to support a pipe in line with the mold supported on the mold-supporting plate, and mechanism for imparting an intermittent rotary movement to said mold-support, whereby the molds are brought successively under said upright frame, substantially as set forth.
12. In apparatus for forming articles of glassware, the combination with a suitable frame, of a rotary mold-support mounted therein adapted to rotate in a vertical plane and having a plurality of rotary mold-supporting faces, mold-supporting plates journaled in said faces and vertical shafts, each of said mold-supporting plates mounted on a vertical shaft, bevel-pinions on said vertical shafts, counter-shafts journaled in said mold-support, bevel-pinions on said counter-shafts meshing with said first-mentioned bevel-pinions, said counter-shafts having clutch-faces, a reversely-rotatable clutch-shaft having a clutch adapted to engage successively with the first-mentioned clutch-faces, and mechanism for rotating said clutch-shaft in opposite site directions, substantially as set forth.
- In testimony whereof I, the said CHARLES E. SCHMUNK, have hereunto set my hand.
CHARLES E. SCHMUNK.
